UNITED STATES PATENT OFFICE.

JOSEPH A. PUTT, OF MARLBOROUGH, OHIO, ASSIGNOR OF ONE-HALF TO
ISAIAH S. FRANCE, OF SAME PLACE.

BRAKE FOR HAY-WAGONS.

SPECIFICATION forming part of Letters Patent No. 296,620, dated April 8, 1884.

Application filed January 25, 1884. (No model.)

To all whom it may concern:

Be it known that I, JOSEPH A. PUTT, a citizen of the United States, residing at Marlborough, in the county of Stark and State of Ohio, have invented certain new and useful 5 Improvements in Wagon-Brakes for Hay-Racks; and I do hereby declare that the following is a full, clear, and exact description of the same, reference being had to the annexed 10 drawings, making a part of this specification, and to the letters and figures of reference marked thereon, in which—

Figure 1 is a side elevation. Fig. 2 is a top view. Fig. 3 is a longitudinal section of rock-bar and its parts. Fig. 4 is a transverse section of rock-bar.

The present invention has reference to means for attaching and operating brakes for hay-racks; and it consists in the construction and 20 combination of parts hereinafter particularly set forth and claimed.

Similar letters of reference indicate corresponding parts in the drawings.

In the accompanying drawings, A represents the ladder or frame, which is preferably 25 attached to the front or forward end of the rack by means of the rock-bar *a*. Said rock-bar is attached to the rack in the ordinary manner, and is provided with a suitable support and bearing for the bottom or lower end of the 30 brake-rod *B*. The top or upper end of this ladder is also provided with a suitable bearing for the top or upper end of the brake-rod *B*. The rock-bar *a* is provided with the cog-wheel *C*, located as shown, and is rigidly 35 attached to the revolving shaft *D*. The cog-wheel *C* should be grooved, for the purpose hereinafter specified.

The brake-rod *B* may be of ordinary round 40 iron, located on the ladder as shown, its top or upper end being provided with the crank *b*. An ordinary brake-wheel may be used, if desired, in place of the crank *b*. The bottom or lower end of this brake-rod is provided 45 with a screw, *d*, as shown in the drawings. This screw may be formed in the rod, or it

may be formed separate and attached, and is for the purpose of operating the several parts of the brake, as hereinafter described.

The object of forming a groove upon the 50 cog-wheel *C* is to give more working-surface for the screw *d*.

To the outer end of the shaft *D* is attached the arm or lever *E*, to which arm or lever is attached the connecting-rod *F*. The rear end 55 of said rod *F* is attached in the ordinary manner to the brake-lever *G*, as shown in the drawings.

The construction described forms a very simple and effective means for operating the 60 brake from either the top of a load of hay or from any position from a horizontal to a perpendicular when the wagon is without a load.

Having now fully described my invention, what I claim as new, and desire to secure by 65 Letters Patent, is—

1. The combination of the hinged frame, the pinion, and revolving shaft connected with the lower end of the frame, the rod supported by 70 said frame, and provided at its lower end with a screw meshing with said pinion, the brakes, and means connecting the same with the revolving shaft carrying the pinion, substantially as described.

2. The combination of the frame connected 75 to the wagon at its lower end by a rock-bar, a revolving shaft journaled in said rock-bar, and provided with a pinion fitting in an opening made in said bar, a rod journaled in suitable bearings on said frame, and provided with 80 a screw at its lower end, meshing with said pinion, the brakes, and the rod connecting them with the pinion-shaft, substantially as described.

In testimony that I claim the above I have 85 hereunto subscribed my name in presence of two witnesses.

JOSEPH A. PUTT.
